10 Claims. (Cl. 252—1)

If alkyl or aryl halides are allowed to act on thiourea a smooth addition takes place and products are formed of a salt-like character. These addition compounds are derived from an isomeric form of thiourea, namely isothiourea, since their whole behaviour indicates that the alkyl or aryl residue appears to be combined to the sulphur. The following constitutional formula therefore is given to these compounds:

0 [NH₂.C.(SR):NH]hlg

wherein "hlg" denotes halogen and "R" a substituted or non-substituted alkyl or aryl radical or a salt thereof. The products are readily soluble in water. The halogen contained in them can be replaced by other acid ions.

It has been found that the aqueous solutions of the S-alkyl and S-aryl isothiourea salts possess a very high capillary activity, particularly when the alkyl or aryl residue added on possesses a molecular weight which is not too low. Thus, for example, solutions of S-dodecylisothiourea chloride form a very stable froth even at high dilution and possess considerable wetting powers with respect to animal, vegetable and artificial fibres. Exactly the same holds for the corresponding decyl, tetradecyl and hexadecyl derivatives. The choice of the anion is of secondary importance since all the essential properties, that is to say, the capillary depression froth formation, etc., are for the most part independent of the nature of the anion. In the case of members of the alkyl or aryl isothiourea series of higher molecular weight, (tetradecyl and S-hexadecylisothiourea) a very satisfactory dispersing and cleansing property is obtained in addition to the properties already mentioned. These products are superior to normal soaps inasmuch as their soap-like character is maintained even when acids are added, and consequently the acid-washing process, which is of importance in the washing of wool, can be carried out herewith without difficulty.

Since in the isothiourea salts the constituent of the molecule which is characteristic for the capillary active action appears in aqueous solution in the form of a positive ion, emulsions can be made herewith in which the particles of the emulsion possess a positive electric charge. Isothiourea salts are particularly well suited for adding to dye baths of basic dye-stuffs, since, in contradistinction to most commercial products, they do not flocculate basic dyestuffs and they ensure a satisfactory and uniform thorough dyeing.

Since the properties of the isothiourea derivatives depend to only a subsidiary extent on the

special nature of the added alkyl or aryl residue, isothiourea salts with other non-substituted or substituted hydrocarbon residues can be used with similar success. The following compounds amongst others come into question:—

5 [NH₂.C.(S.CH₂.CH₂.O.C₁₂H₂₅):NH]Ac[NH₂.C.(S.CH₂.CH₂.OOC.C₁₁H₂₃):NH]Ac[NH₂.C.(S.CH₂.COO.C₁₀H₂₁):NH]Ac

10

NH₂.C.(S.C₆H₅. ortho NH₂.para NHCO₂C₆H₅):NH]Ac

wherein "Ac" indicates an acid residue, such as chlorion.

Finally reference must be made to the possibility of making S-alkyl and S-aryl iso-thiourea salts in which the amide or imide hydrogen atoms are replaced by any desired organic residues and which, as regards their behaviour, follow the aforementioned products.

20 What we claim is:—

1. A process for enhancing the efficiency of treating liquids for animal, vegetable or artificial fibers, comprising the addition to known treating agents for fibrous materials of a compound of the general formula [NH₂.C(SR):NH]Ac, wherein "R" means a radical selected from the group consisting of the alkyl and aryl radicals, and "Ac" means an acid radical.

2. A process for enhancing the efficiency of 30 treating liquids for animal, vegetable or artificial fibers, comprising the addition to known treating agents for fibrous materials of a compound of the general formula [NH₂.C(SR):NH]Ac, wherein "R" means a radical selected from the group consisting of the alkyl and aryl radicals wherein a hydrogen atom is substituted by an alkoxy group.

3. A process for enhancing the efficiency of 35 treating liquids for animal, vegetable or artificial fibers, comprising the addition to known treating agents for fibrous materials of a compound of the general formula [NH₂.C(SR):NH]Ac, wherein "R" means a radical selected from a group consisting of the alkyl and aryl radicals, wherein a 40 hydrogen atom is substituted by an alkylimine group.

4. A process for enhancing the efficiency of 45 treating liquids for animal, vegetable or artificial fibers, comprising the addition to known treating agents for fibrous materials of a compound of the general formula [NH₂.C(SR):NH]Ac, wherein "R" means a radical selected from a group consisting of the alkyl and aryl radicals, wherein a 50 hydrogen atom is substituted by an alkoxy group.

5. A process for enhancing the efficiency of treating liquids for animal, vegetable or artificial fibers, comprising the addition to known treating agents for fibrous materials of a compound of the general formula $[\text{NH}_2\text{C}(\text{SR})\text{:NH}]\text{Ac}$, wherein "R" means an alkyl radical with from 12 to 16 carbon atoms.
6. A process for enhancing the efficiency of treating liquids for animal, vegetable or artificial fibers comprising the addition to known treating agents for fibrous materials of a compound of the general formula $[\text{NH}_2\text{C}(\text{SR})\text{:NH}]\text{Ac}$, wherein "R" means the n-dodecyl radical.
7. A process for enhancing the efficiency of treating liquids for animal, vegetable or artificial fibers, comprising the addition to known treating agents for fibrous materials of a compound of the general formula $[\text{NH}_2\text{C}(\text{SR})\text{:NH}]\text{Ac}$, wherein "R" means the n-hexadecyl radical.
- 20 8. A product for treating liquids for animal,

vegetable and artificial fibers, comprising a known agent for improving the properties of said fibers, in combination with a compound of the general formula $[\text{NH}_2\text{C}(\text{SR})\text{:NH}]\text{Ac}$, wherein "R" means a radical selected from the group consisting of the alkyl and aryl radicals and "Ac" means an acid radical. 5

9. A product for treating liquids for animal, vegetable, and artificial fibers, comprising a known agent for improving the properties of said fibers in combination with S-dodecyl isothiourea halogenide.

10. A product for treating liquids for animal, vegetable, and artificial fibers, comprising a known agent for improving the properties of said fibers in combination with S-dodecyl-isothiourea chloride.
